UNITED STATES PATENT OFFICE.

WALTER GILLET, OF CLEVELAND, OHIO.

CARBURETER.

1,101,736.

Specification of Letters Patent. Patented June 30, 1914.

Application filed July 26, 1911. Serial No. 640,643.

To all whom it may concern:

Be it known that I, WALTER GILLET, a subject of the King of Great Britain, residing at Cleveland, in the county of Cuyahoga and State of Ohio, have invented a certain new and useful Improvement in Carbureters, of which the following is a full, clear, and exact description, reference being had to the accompanying drawings:

10. This invention relates to carbureters, and has for its general object the provision of a construction whereby the mixture may be automatically enriched at times when the piston speed of an engine is lowered while 15 the throttle valve is substantially wide open, as will occur when the engine is subjected to heavy load, a familiar instance being afforded by an automobile climbing a hill. In carrying out my invention in the ex- 20 amplification shown herein, a valve of the rotary plug type is provided having a passageway therethrough, communicating at one of its ends with the air inlet port and at its opposite end with the induction conduit 25 leading to the engine, said passageway constituting the mixing chamber of the carbureter. Gasoline is supplied to the mixing chamber through a jet which projects into the passageway through one end of the 30 valve plug along the longitudinal axis thereof. Within the passageway is an obstructing means which will automatically restrict the area of said passageway and lessen the quantity of air conducted therethrough when the piston speed is reduced. In the specific embodiment shown herein, the obstructing means is a leaf or vane so arranged as to be capable of partially obstructing the passageway of the valve but which 35 may be moved, through the suction produced by the piston or pistons operating at high speed, to non-obstructing position. When this suction falls, through reduction of piston speed, a spring tends to move the 40 leaf or vane into obstructing position, thus reducing the effective area of the passageway below the jet orifice, diminishing the flow of air therethrough, increasing the suction upon the jet orifice and enriching the 45 mixture supplied to the engine cylinder or cylinders.

In the drawings forming part hereof, Figure 1 represents a view, partly in section and partly in side elevation, of a carbureter constructed in accordance with my invention; Fig. 2 represents a vertical sec-

tional view of a portion of the carbureter, taken through the valve and corresponding substantially to the line 2-2 of Fig. 1; and Fig. 3 represents a vertical sectional view 60 of the valve and its casing, showing the valve in open position.

The carbureter shown herein is of the same general type as that illustrated, described and claimed in my application No. 65 544,739, filed February 19th, 1910, and comprises generally the following parts:—1 denotes a float feed chamber having the removable cover 2 thereon and the supply connection 3 projecting into the bottom. The 70 bottom of this chamber is provided with a hollow boss 4 projecting laterally therefrom, which boss is provided with a discharge port 5, the said boss communicating with the interior of the chamber 1 and being provided 75 with a valve 6 by means of which the interior of the chamber may be drained through the outlet 5.

Projecting from the chamber 1, and preferably cast therewith, is a casing 7 for the 80 accommodation of the rotary plug valve, the air inlet port and the induction conduit. To the bottom of this casing 7 there is secured an air admission member 8, conveniently formed of a casting having a lateral 85 inlet port 9, there being a concaved or dished circular valve 10 carried by the upper end of the stem 11 which is threaded into the member 8 and provided with a suitable thumb screw 12. The valve and its stem are 90 located in line with the axis of the induction passageway 13 provided in the casing 7. The casing 7 is provided with a cylindrical bore extending transversely thereof, said bore being of considerably greater 95 diameter than that of the passageway 13 and forming a seat for the rotary throttle valve plug 14. This plug is provided with a passageway 15 adapted to register with the induction conduit 13, and with the air inlet 100 port, all of which are of the same diameter. One end of the plug is provided with a neck 16 projecting through a disk 17, which disk may be secured to the casing 7 in any convenient manner. The neck 16 is provided 105 with an operating crank 18, which may be connected with the throttle lever. The crank is shown as secured to the neck by means of a pin 19. The side of the casing 7 opposite the neck 16 is provided with a 110 boss 20, said boss being internally threaded for the reception of a screw cap 21. Gaso-

lene from the float feed chamber 1 enters the interior of this boss at a point near the inner end of the latter. The jet plug 22 is mounted in this boss, said plug being provided with a pair of spaced integral collars 23 provided each with threads adapted to mesh with the threads within the boss. The outer end of this plug is preferably squared, for the reception of a wrench. The inner portion of the plug is reduced and projects through the casing 7 and the axial portion of the plug 14 and substantially as far as the center or axis of the passageway 13. The plug is provided with a bore 24 extending therethrough and with a lateral port 25, between the collars 23, whereby gasoline supplied to the inner end of the boss 20, between said collars, may enter the jet plug.

26 denotes the obstructor which I employ for the purpose of reducing the area of the passageway below and increasing the suction upon the jet orifice 27. The obstructor is shown as a leaf or vane, preferably of light metal, which is pivoted within the valve 14. The pivot 28 extends across the central portion of the passageway in said valve and, when the valve is fully open, is below the jet orifice 27. The leaf 26, with the parts in this position, extends upwardly and toward one side of the passageway and is of such shape as to contact with the wall of the passageway, the upper edge of the leaf, when in full obstructing position, being adjacent to the small port 29 provided at the outlet edge of the valve 14, as shown clearly in Fig. 1. The lower end of the leaf 26 extends a short distance beyond the pivot 28, as shown at 30, to provide a partial counterbalance for the part on the other side of the pivot, thus allowing the use of a more sensitive spring. Furthermore, the passageway 13 is thus further obstructed.

For the purpose of normally retaining the leaf in full obstructing position, the following construction is provided:—31 denotes a sleeve which is threaded into the neck 16, axially thereof, the sleeve preferably projecting into the interior of the valve 14. Mounted centrally within this sleeve is a spindle 32, said spindle extending entirely through the sleeve and having at its inner end an arm 33 which is adapted to engage the upper edge portion of the leaf 26. At its outer end, the sleeve 31 is provided with a cup 34, and in this cup there is slidably mounted the cap 35 to which the outer end of the spindle 32 is secured. A spring 36 surrounds the outer portion of the stem 32, within the cup 34, and is connected at one end to the sleeve (through the cup 34) and at its other end to the cap 35, and is so arranged that it tends to rotate the spindle 32 in a direction to hold the outer end of the arm 33 in engagement with the leaf or obstructor 26. For the

purpose of adjusting the tension of the spring 36, and thus varying the amount of "suction" necessary to rock the leaf 26 on its pivot, the sleeve 31 is rotatable with respect to the spindle 32 and is conveniently retained in adjusted position by the engagement of the outer end of a spring 37 with a series of projections 38 at the inner end of the cup 34. The spring 37 may be conveniently carried by the arm 18, since the sleeve 31 rotates with the valve 14. The rotary plug 14 is preferably of the same type as shown in my application 544,739. The lower or inlet portion of the plug is provided with a port 39 therethrough, which may be substantially acorn shaped, as is the case with the port in the plug shown in my aforesaid application. In addition to this port, a port 40 is provided on each side of the port 39 and between the last mentioned port and the inlet edge 14* of the valve. The ports 40 may be substantially key-hole shape, as is the case of my aforesaid application. Furthermore, the outlet portion of the valve may be provided with a port 41 located near the edge of the outlet portion of the valve, opposite the port 29.

From the foregoing construction and description, it is believed that the operation will be evident. By reference to Fig. 1, it will be seen that, when the valve is closed or nearly closed, the obstructor will have no effect upon the operation of the carbureter. When the valve is even more than half open, the arrangement and shape of the obstructor are such that it will be practically ineffective, and it is not until the valve is more than half open that the obstructor can become effective. When the valve is fully open, which is the case when running at high speed and under heavy load (as when climbing a hill) the obstructor is in position to develop its maximum efficiency. With the pistons running at high speed, the obstructor will extend substantially vertically in the passageway 15 (as shown in dotted line in Fig. 3) and will have no appreciable effect upon the mixture. When the pistons run at lower speed, as when under heavy load, the spring-pressed arm 33 will hold the obstructor in contact, or in substantial contact, with the adjacent wall of the passageway (as shown in full line in Fig. 3) thereby automatically reducing the cross sectional area of this passageway at the inlet end and below the jet orifice 27. This reduces somewhat the quantity of air supplied to the mixing chamber and increases the proportion of gasoline, with the result that the mixture is enriched and the engines are enabled to develop more power on account of such enriching. In dot and dash line, in Fig. 3, the obstructor is shown in the position which it will assume for intermediate piston speeds.

While my invention is shown as applied to a carbureter, of the type disclosed in my earlier application hereinbefore referred to, certain features of construction are applicable to other environments and to cases wherein a throttle valve is provided separate from the mixing chamber as well as where the valve forms part of such chamber. Hence, though the invention is necessarily described in detail in connection with the exemplification shown herein, I do not propose to be limited to such details except as the same may be positively included in the claims hereto annexed or rendered necessary by the prior state of the art.

Having thus described my invention, what I claim is:

1. In a device of the character set forth, the combination of a rotary valve having a passageway extending therethrough constituting a mixing chamber, a casing for said valve having openings adapted to register with said passageway, a jet nozzle projecting into said valve and into said passageway, an obstructing device located at one side of said passageway and between the jet nozzle and such side and arranged, when closed, to prevent the flow of fluid through such side of the passageway, a spring for resisting the opening movement of the obstructing device, and means whereby the tension of said spring may be adjusted.

2. In a device of the character set forth, the combination of a casing having an induction conduit, a valve within said casing adapted to govern the flow of air through said induction conduit a jet nozzle for conveying liquid fuel to the column of air which passes through the conduit, an obstructing device located at one side of said nozzle and arranged to resist the flow of fluid through the conduit, and a spring resisting the movement of the obstructing device to non-obstructing position.

3. In a device of the character set forth, the combination of a rotary valve having a carbureting chamber therein having ports, a casing for said valve having passageways adapted to register with said ports, a jet nozzle projecting into said valve and into said chamber, an obstructing device pivoted below said nozzle and extending upwardly from its pivotal support and into substantial contact with a wall of the carbureting chamber at one side of the nozzle and adapted in such position to substantially prevent the flow of fluid between itself and the adjacent wall of the carbureting chamber, an arm engaging the obstructing device, and a spring arranged to hold the arm in contact with said device.

4. In a device of the character set forth, the combination of a rotary valve having a passageway extending therethrough, a casing for said valve having passageways adapt-

ed to register with the passageway within the rotary valve, a jet nozzle projecting into said valve and passageway, a leaf or vane pivotally mounted on the inlet side of said passageway and adapted to contact with the wall 70 of the passageway at one side of the nozzle, a spindle projecting into the valve opposite the jet nozzle, an arm projecting from said spindle and adapted to engage the leaf or vane, a spring connected with said spindle 75 in such manner as to hold the arm in engagement with the leaf or vane, and means located outside of the valve for adjusting the tension of the spring.

5. In a device of the character set forth, 80 the combination of a rotary valve having a carbureting chamber therein having ports, a casing for said valve having passageways adapted to register with said ports, a jet nozzle projecting into said valve and said chamber, a leaf or vane pivotally supported 85 on the inlet side of said chamber with respect to the jet nozzle and adapted to contact with the wall of said chamber at one side of the nozzle, means for rotating said 90 valve, means including a spring for resisting the movement of the vane or leaf away from the coöperating wall of the carbureting chamber, said means being rotatable with the valve, and means whereby the tension of 95 the spring may be adjusted independently of the valve-rotating means.

6. In a device of the character set forth, the combination of a rotary plug having a passageway therefor, a casing for said valve 100 having ports adapted to register with the passageway in said valve, a jet nozzle projecting into said plug, a leaf or vane pivoted below said nozzle and extending upwardly from its pivot and adapted to contact with the wall of the passageway at one side of the jet nozzle, a spindle projecting into the valve port opposite the nozzle, an arm carried by said spindle and adapted 105 to engage the leaf or vane, a spring surrounding the outer portion of said spindle and connected therewith in such manner as to hold the arm in engagement with the vane or leaf, and a member mounted within the wall of the valve and surrounding 110 a portion of the spindle and connected to the opposite end of the spring, said member being rotatably adjustable with reference to the spindle and rigidly connected with the valve wall.

7. In a device of the character set forth, the combination of a casing having an induction conduit, a rotary valve extending across said conduit and provided with a passageway adapted to register with and form part of said conduit, a jet nozzle within said passageway, and means within said passageway for automatically varying the cross sectional area thereof in the vicinity of the jet nozzle when the port is nearly 125 130

- register with the induction conduit, said valve being provided with a port whereby the proportions between the inlet to and outlet from the passageway may be varied.
- 5 8. In a device of the character set forth, the combination of a casing having an induction conduit, a rotary valve plug having a passageway extending therethrough and adapted to register with said induction conduit and provided with a jet nozzle in said passageway, means whereby the effective area of the passageway on the inlet side of the jet nozzle may be automatically varied when the passageway is nearly in register
- 10 15 with the induction conduit, and means whereby the proportions between the areas of the inlet and outlet of the passageway may be varied when the valve approaches its closed position.
9. In a device of the character set forth, 20 the combination of a casing having an induction conduit extending therethrough, a rotary plug valve extending across said conduit and provided with a passageway adapted to register with said conduit, a jet nozzle within said passageway, and means located within said passageway and arranged to restrict the area of the passageway in the vicinity of said nozzle only when the passageway substantially registers with said 25 conduit.
- 10 15 In testimony whereof, I hereunto affix my signature in the presence of two witnesses.

WALTER GILLETT.
